(57) **CLAIM**

The ornamental design for a containment clip, as shown and described.

DESCRIPTION

FIG. 1 is a perspective view of a containment clip showing my new design;

FIG. 2 is a front view thereof, the rear view being a mirror image;

FIG. 3 is a top view thereof;

FIG. 4 is a bottom view thereof;

FIG. 5 is a left side view thereof; and,

FIG. 6 is a right side view thereof.

The broken lines depict portions of the containment clip that form no part of the claimed design.

1 Claim, 2 Drawing Sheets
